UNITED STATES PATENT OFFICE.

MARVIN C. ROBERTS AND HUBERT J. CULLUM, OF FRANKLIN, ILLINOIS.

RAILROAD-SPIKE.

1,158,293.

Specification of Letters Patent.

Patented Oct. 26, 1915.

Application filed January 25, 1915. Serial No. 4,301.

To all whom it may concern:

Be it known that we, MARVIN C. ROBERTS and HUBERT J. CULLUM, citizens of the United States, residing at Franklin, in the county of Morgan and State of Illinois, have invented certain new and useful Improvements in Railroad-Spikes; and we do hereby declare the following to be a full, clear, and exact description of the invention, such as will enable others skilled in the art to which it appertains to make and use the same.

This invention relates to new and useful improvements in railroad spikes and has for its principal object to provide a spike which will effectively hold railroad rails in place and which will prevent the rails from spreading, shrinking or creeping.

Another object of the invention is to provide a spike which after having been driven into the tie can be locked therein, thus preventing the spike from working loose and permitting the rail to slip.

A further object of the invention is to provide a locking spike which may be withdrawn should it be so desired.

With these and other objects in view, the invention consists in the novel combination and arrangement of parts which will be fully set forth in the following specification and accompanying drawing, in which—

Figure 1 is a side view in elevation of a spike constructed in accordance with this invention showing the lock in place, Fig. 2 is a vertical sectional view of Fig. 1, Fig. 3 is a detail view in elevation of the lock, and Fig. 4 is a sectional view taken on line 4—4 of Fig. 1, and looking in the direction of the arrows.

Referring now to the drawing, by characters of reference, the numeral 1 designates as an entirety a spike constructed in accordance with this invention and comprising a body 2 having formed at its upper end the head 3. This body is provided at its lower end with the point 4 which is designed to be driven into the tie in the usual manner. Formed centrally of the body 2 is the rectangular passage 5 which extends axially into the spike and communicates with the rectangular arcuate passage 6, which communicates at 7 with the passage 5 and at the point 8 with an opening in the side of the spike. The upper end of the passage 5 is preferably provided with the outwardly and upwardly inclined wall 9, the use of which will appear as the description proceeds.

The spike lock designated generally by the numeral 10 comprises the body 11, having formed at one end the point 12 and at the opposite end the frusto pyramidal head 13, the faces of this head are inclined to conform to the inclination of the wall 9, as clearly shown in Figs. 1 and 2. Formed centrally of the upper face of the head 13 is the rectangular shank 14, having formed at its free end the head 15. The whole lock 10 is formed of a relatively ductile metal which will easily bend as clearly illustrated in Figs. 1 and 2.

It will be apparent from the foregoing that in use the spike 1 is first set and driven into the tie in the usual manner. The lock 10 is then set so that the pointed end 12 extends into the passage 5 and will pass therethrough until the side walls thereof engage the arcuate portion 6 at the point 7. The user then strikes the lock upon the head 15 thereby driving the same downwardly so that the sides of the body 11 engage the arcuate passage thus causing the body to bend and upon continuing the driving operation, it will be apparent that the end of the lock 10 will pass through the rectangular opening at the side of the spike and thence be driven into the wood of the tie thereby locking the spike firmly in place and eliminating the danger of accidental removal. The lock 10 is driven downwardly until the inclined faces of the frusto pyramidal head engage the outwardly inclined faces 9 thus forming a stop which will be water-proof, thereby preventing the lock from rusting in the passage. Should it be desired to place a new tie in the track, the lock may be withdrawn by placing a suitable pulling tool in position to operate upon the head 15 thereof and thus pulling upwardly thereon and raising the lock from its position in the spike. After the lock has been withdrawn it is apparent that the spike may be withdrawn in the ordinary manner and a new tie placed in position.

While in the foregoing there has been shown and described the preferred embodiment of this invention, it is to be understood that such changes may be made in the combination and arrangement of parts as will fall within the spirit and scope of the invention as defined in the appended claim.

What is claimed is:—

A locking spike including a spike body having a central axial passage formed there-

in, the upper end of the passage being enlarged to form a countersink, the body being provided with an arcuate passage and an aperture, said arcuate passage connecting the 5 aperture with the axial passage, a lock arranged to be driven into the axial and arcuate passages and out through the aperture, a frusto pyramidal head formed on the lock arranged to engage the inclined 10 faces of the upper end of the passage to form a water tight joint between the lock

and the spike and prevent the lock from rusting in the spike, a shank formed on the frusto pyramidal head and a head on the shank.
